UNITED STATES PATENT OFFICE.

GEORGE TAYLOR AND JAMES HENRY TAYLOR, OF NOTTINGHAM, COUNTY OF NOTTINGHAM, ENGLAND.

PLAITING-MACHINE.

SPECIFICATION forming part of Letters Patent No. 334,060, dated January 12, 1886.

Application filed September 26, 1884. Serial No. 144,027. (No model.)

To all whom it may concern:

Be it known that we, GEORGE TAYLOR, residing at 245 Great Alfred Street, in Nottingham, and in the county of Nottingham, England, and JAMES HENRY TAYLOR, residing at 16 Gladstone Street, Nottingham, and in the county of Nottingham, England, and subjects of the Queen of Great Britain and Ireland, have made a new and useful Improvement in
10 Machines for Forming Plaits and Flutes in a Strip of Goods, and I do hereby declare that the accompanying specification, when taken in connection with the drawings attached thereto, give such a full, clear, and accurate
15 description of our invention that others skilled in the art can practice the same.

Our invention relates to machines which form and press down into permanent shape plaits in a strip or strips of textile material
20 passed through the machine.

Before the date of our invention it was common to make gathers or puckers in goods by the use of the Arnold double-feed sewing-machine, or the double-feed machine patented to
25 Singer; but such puckers or gathers were not regular—or, in other words, were not all laid in one direction—and scarcely could be called plaits.

The first plaiting-machine that made regular and even plaits was patented to Crosby and Kellogg. This machine, by means of a reciprocating knife, formed plaits of any desired size in a strip of goods, which plaits were passed under a presser-foot, and were
35 sewed down by a sewing-machine.

Various modifications of this machine have been used, notably that modification in which a reciprocating knife and two intermittently-operated rolls were used.

40 The reciprocating knife of Crosby and Kellogg has been the common device used in connection with all subsequent machines up to the present day for making plaited goods.

We are well aware of the fact that fluting-
45 machines of various kinds have long existed—that is to say, machines which formed the fabric into semicircular flutes, not pressed down in either direction by the machine. We are also well aware of the fact that such fluted
50 goods have been passed through mechanism

which flattened out the flutes into box-plaits. None of these old machines show our invention, which consists of a machine which operates substantially as follows upon a piece of goods fed into it: The goods are first passed 55 through two rollers having ratchet-teeth, which form the goods into a succession of transverse ridges, each of which consists of a vertical and a sloping side, the sloping side of each ridge being toward the operator and the vertical 60 side facing the rest of the mechanism of the machine. Although these ridges may, it is not intended that they should in all cases, form all the final lines upon which the material is bent in forming the final plait, these ridges 65 being formed so that the goods will be bent upon some line, which line of bend may subsequently be altered to change the fullness of the goods. After passing between these ratchet-teeth rollers the goods move over a table, 70 preferably, and from there pass on to the surface of a cylindrical feeding-roller having preferably a roughened surface, and under a guard-plate or guide, which is appropriately held over a portion of the surface of said feed-75 roller. As the goods pass between the under side of this guide-plate and the surface of the feed-roller, they are acted upon by laying-wheels, which operate through slots in the guide-plate and force the goods to enter between the roller and the guide-plate, with their plaits lying all in one direction, the laying-wheels moving rapidly, and preferably having an indented or ratchet-tooth surface, which acts upon the plaits, insuring their even dis-80 position between the feed-roller and the guide-plate. After passing from under the guide-plate the goods are carried on by means of the feed-roller and a second or adjacent feed-roller, which is pressed into proximity to the adjoining roughened feed-roller. These two feed-rollers together give the final pressure to the plaits, and finally lay them so that they may at a subsequent operation be sewed by a sewing-machine. The speed of the two 85 feed-rollers determines the fullness of the plaits. It is evident that if the surface-speed of the feed-rollers is identically the same as the surface-speed of the ratchet-tooth crimping-rolls, all the feed-roller would do would be to 90 95 100

lay flat and make permanent the plait formed by the ratchet-tooth rolls; but if the feed-rolls are moved at a faster speed than the ratchet-tooth rolls, it is evident that a certain amount of the fullness of the goods will be taken away and the plaits will be smaller and the spaces between them greater than would be the case did the feed-rolls and the ratchet-tooth crimping-rolls rotate together at the same speed. Thus by regulating the speed of the feed-rolls the goods may be produced with plaits as wide as would be due to the ratchet-tooth rolls; or by increasing the speed of the feed-rolls over that of the ratchet-tooth rolls the plaits may be made comparatively narrow and the spaces between them be made comparatively large.

We use in our machines heat to set the creases in the goods, and we may use gum 20 cords, which are caused to adhere to the plaited goods.

It will be seen that as our machine uses no reciprocating parts, as did the Crosby and Kellogg machine, its operation can be made very 25 rapid, which is a feature of great importance in manufacturing long strips of goods with fine transverse plaits.

Our machine may be so arranged as to make, in connection with plaits, flutes also. This we 30 accomplish by making either the center or the end or ends of the feed and pressure rollers so that they press down the crimps, leaving the remaining portions of the surface of the feed and pressure rollers so that they do not 35 touch each other. Thus the crimped goods are not pressed into plaits at such parts, but remain as crimps in the goods, which crimps may be given the appearance of flutes by so forming the crimping-rolls as to thus shape the 40 goods. When thus formed, the crimping-rolls do not produce such folds in the goods as are the most advantageous for forming plaited goods; but as in these cases the plaited portion is but an inconsiderable width of the strip 45 this disadvantage is not serious.

Referring to the accompanying drawings, Figure 1 is a side view of the machine; Fig. 2, a similar view with the pulley and gear-wheels on the near side removed. Fig. 3 is an elevation of the machine, seen from the opposite side. Fig. 4 is an elevation in section corresponding to Fig. 1. Fig. 5 is a plan of the machine. Fig. 6 is a vertical section, corresponding to Fig. 4, showing certain modifications. Fig. 7 is a plan of the feed and pressure rollers shown in Fig. 6.

Similar letters of reference indicate corresponding parts in all the figures.

Referring to Figs. 1 to 5, the frame of the 60 machine consists of two pieces, A A', connected with each other by stay-bars a , and bolted to a bed-plate, A^2 , as shown. The motion of all the parts is derived from a pulley, B, turning upon a stud, b , and to which pulley 65 is rigidly attached a pinion, b' , which latter, through an intermediate pinion, b^2 , upon stud

b^3 , imparts motion to the wheel C upon the axis of the lower one of the two fluting-rollers D E. The roller D is mounted in bearing-plates d , which are adjustable upon the side 70 frames, as shown in Fig. 2, and the roller E is pressed into contact with the roller D by means of springs e , acting on its sliding journal-blocks e' . The force of the springs e may be adjusted by turning the thumb-screws e^2 in one direction or the other, as the thickness of the goods passing between the rollers D E or other circumstances may require. The crimping-rollers D E are formed on their surface with ratchet-teeth of proper shape to form in the goods 80 passing between them flutes or ridges, each flute being composed of one inclined and one vertical or nearly vertical portion. For reasons that will appear further on it is important that the rollers be placed in the machine 85 so that the inclined portions of the flutes formed in the goods will have the direction from the point of entrance upward and forward toward the point where the goods leave the rollers. The upper roller, E, receives its 90 motion from the roller D, through the wheels $d' e'$, near the side frame, A'. The goods entering the machine pass over a perforated table, a' , their edges being guided in the laterally-adjustable ways a^2 . If desired, a jet of 95 steam may be caused to issue from a pipe or nozzle, a^3 , Fig. 4, below the table a' , which jet, rising through the perforations in the table a' , will strike the strip of goods in a finely-divided condition and slightly moisten the same, 100 so that the ridges formed by the preferably heated rollers D E will be more efficiently set. The strip of fabric, after passing through the fluting-rollers D E, passes over a table, a^4 , toward and onto the first feed-roller, F, which 105 latter is preferably slightly roughened on its surface, and turns in bearing-plates f , which are adjustable in a manner similar to those d of the roller D. The second feed-roller, G, is held in contact with the roller F by means of 110 its sliding journal-blocks g , springs g , and screws g^2 in a manner analogous to the roller E. The rollers F and G are geared together by means of the wheels $f' g^3$, and the roller F carries on its opposite end a wheel, f^2 , which 115 gears into a wheel, H, attached to and turning upon the same axis with the wheel H' , the latter gearing into the wheel d' upon the roller D. It will be seen that by exchanging the wheel H for one of larger or smaller diameter 120 the surface velocity of the feed-rollers F G may be varied with relation to the surface velocity of the fluting-rollers D E. The exchanging of the wheel H, as indicated, is rendered possible by mounting the stud carrying 125 the rigidly-connected wheels H H' in a piece, h , which is adjustable upon the side frame, A', as shown in Fig. 3. While the goods are passing over the feed-roll F, the ridges or flutes are made—or, in other words, the plaits are completed—and, if desired, the effect of the laying 130 may be rendered more permanent by the ap-

plication of a gummed thread along one or more lines of the plaited strip. This laying and completing of the plaits is effected by the following mechanism: I I is a series of toothed laying-wheels carried upon a shaft, I', which turns in adjustable bearing-plates *i*, so that the distance between the periphery of the roller F and wheels I may be regulated with great nicety, in accordance with the work being done. 5 The shaft I' receives its motion through the wheel *i'* and intermediate wheels, *i' i''*, from wheel C, the diameter being so proportioned as to give the shaft I' and wheels I a considerably quicker motion than have either the 10 rollers D E or F G. The result of this arrangement is that as the tops of the ridges or flutes formed in the fabric by the rollers D E come in contact with the rapidly-revolving wheels I they are moved forward faster than the bottom or lower portions of the flutes, and are thus laid or pressed down toward the surface of the roller F, thus forming perfect plaits. 15 Immediately after the plaits are thus laid the fabric enters into a space formed by the surface of the roller F and the convex surface of a guide-plate, J, which latter serves to keep them in the laid condition until they arrive and become firmly pressed between the roller F and the second feed-roll, G, which latter, as 20 above stated, is held with considerable force against the roller F by means of the springs *g*.

In order to facilitate the entrance of the plaited fabric under the plate J without disturbing the plaits, the front edge of the plate 35 J is brought forward to a point where the plaits are still acted upon by the wheels I, slots being formed in the plate J, as shown, to accommodate the wheels I. In this manner the plaits are positively laid and held down 40 by the wheels I while entering the space between the plate J and the roller F, and are not acted upon by said wheels after having advanced some distance under the plate J. The latter is supported by the rods *j*, which 45 slide in the pieces *j'*. The springs *j''*, surrounding the rods *j* and abutting against the pieces *j'* at the top and against the plate J below, serve to hold the latter with an elastic force at the desired distance from the roller 50 F, this distance being regulated by the adjusting-nuts *j''*, at the upper end of the rods *j*, bearing against the pieces *j'*. The latter themselves are mounted adjustably upon the stay-bar *j'*, being for this purpose provided with 55 slots *j''*, through which pass the fastening-screws *j''*.

K is a thread-laying wheel, the shaft K' of which is supported in spring-bearings analogous to the roller G, so as to create pressure 60 between the wheel K and roller F. The wheel K works through a slot formed for the purpose in the plate J, and presses one or more gummed threads into firm contact with the plaited fabric, the gum causing said threads 65 to adhere to the fabric, and thus render the plaits more permanent. The threads are de-

rived from one or more spools upon the spool-carrier *k*, and after passing in the gum-trough *k'* are led to the guide-eye *k''* and guide-notches *k''*, whence they pass to the fabric, as indicated 70 in Fig. 4.

So far in this description it has been supposed that the rollers D E and F G move with substantially the same surface velocity. It follows therefrom that the delivery between 75 F G being the same as the feed between D E the plaits will be laid by the wheels I exactly according to the creases formed by the rollers D E.

When, now, it is desired to produce goods 80 with narrower plaits and a correspondingly larger interval between each fold, it will be seen that this can be accomplished by increasing the speed of the rollers F G, because thereby the ridged or crimped fabric as it comes 85 from the rolls D E will be stretched, and the plaits as finally pressed down by the wheels I will not be bent on all of the original lines which formed the ridges in the fabric, but on lines correspondingly nearer the bottom 90 creases in the fabric as the latter is stretched to a greater or less extent. The change of velocity of the rollers F G with relation to the rollers D E is effected, as has been above described, by simply exchanging the wheel H 95 for one of different diameter. The rollers D E F G, with their trunnions, are or may be all cast hollow, so that they may be heated by burning within their interior a mixture of air and gas or gas alone, said gas being introduced 100 through pipes L, passing through the hollow trunnions, as indicated.

Referring to Figs. 6 and 7, when it is desired to produce both plaited and fluted goods this modification may be used. At E D are 105 shown the crimping-rolls between the tables *a' a''*. It will be seen that the crimping-rolls in this case are formed with teeth, which are adapted to make flutes in the goods, and which teeth are shown as square, though they might 110 be slightly rounded. At I is shown one of the laying-rolls, at K the gum-thread roll, and at F and G the feed and pressure rolls. The usual guide-plate, J, is also shown. By referring to Fig. 7 it will be seen that the rollers 115 F G come in contact only at F' and G', thus pressing the goods down into plaits only in the center, the goods on each side of the meeting portions of the rolls F G being left in the fluted condition, or in the same condition in 120 which they leave the rollers E D. The laying-rolls I, which operate upon the goods on each side of the portions F' G', are in substance assistant feeding-rolls, and may either be smaller in diameter, or all of the rolls may 125 be adjusted a little farther away from the surface of the rolls F.

Many modifications may be made in the details without departing from the principles or sacrificing all the advantages of the invention. 130 Certain parts may be used without the others or combined with other mechanism than here-

in indicated. We can combine the plaiting mechanism with a sewing-machine for permanently securing the plaits. The heating of the several rollers may be effected by means of steam, instead of by the burning of gas; or in some cases we can work without heating the rollers at all. In some cases, particularly when a large number of machines is employed, the wheel H may be mounted permanently, so that each machine will produce only plaited goods of one given degree of fullness. Some of the effects of exchanging the wheel H for others of different diameter may be attained by making the rollers D E exchangeable, and having for each machine different sets of such rollers of different degrees of coarseness of teeth, whereby the depth of the preliminary fluting may be varied; but as we usually construct our machines we propose to have the speed of the rollers differentiated, as above explained, so that by increasing the speed of the rollers F G over and above the speed of the rollers E D the fullness of the goods can be thus varied, and goods be produced with more or less plaits to the inch. It will also be observed that all the motions in our machine are rotating motions, and that we use no reciprocating plaiting-blades or the like.

We believe it to be new to form plaits with a machine having no reciprocating parts.

What we claim, and desire to secure by Letters Patent of the United States, is—

1. In a machine for forming and pressing plaits in a strip of fabric, the combination of two grooved crimping-rolls, two feed and pressure rolls, one or more laying-wheels, and a guide-plate extending from the laying-wheels to near the line of contact between the pressure-rolls, substantially as described.

2. In a machine for forming and pressing plaits in a strip of fabric, the combination of two grooved crimping-rolls, two feed and pressure rolls, one or more laying-wheels, and a guide-plate formed with slots, through which the laying wheel or wheels operate, substantially as described.

3. In a machine for forming and pressing plaits in a strip of fabric, a table over which the goods pass and from which they are delivered to two crimping-rolls, and a table or support for the goods as they pass toward the laying mechanism and guide-plate and over the moving feed-surface, in combination with said crimping-rolls, laying mechanism, and moving feed-surface, substantially as described.

4. In a machine for forming and pressing plaits in a strip of fabric, the combination of two crimping-rolls, two pressing rolls, a laying wheel or wheels, a guide-plate extending from the laying-wheels to near the line of contact between the pressing-rolls, and devices for adjusting said guide-plate, and devices for causing it to yield, substantially as described.

5. In a machine for forming and pressing plaits in a strip of fabric, the combination of

two grooved crimping-rolls with a laying mechanism consisting of one or more wheels and means for moving the latter at a high velocity in comparison with the crimping-rolls, substantially as described.

6. In a machine for forming and pressing plaits in a strip of fabric, the combination of one or more laying-wheels with a slotted guide, a moving feed-surface, and devices for imparting motion to said laying-wheels and feed-surface, so constructed as to cause the laying-wheels to move faster than the feed-surface, substantially as described.

7. In a machine for forming and pressing plaits in a strip of fabric, the combination of a series of laying-wheels having roughened surfaces, as shown, with a slotted guide-plate, a moving feed-surface, and devices for imparting motion to said laying-wheels and feed-surface, so constructed as to cause the laying-wheels to move faster than the feed-surface, substantially as described.

8. In a machine for forming and pressing plates in a strip of fabric, the combination of two grooved crimping-rolls, a laying wheel or wheels, two feed and pressure rolls, and devices for imparting motion to these several parts, so constructed as to cause the feed and pressure rolls to revolve at the same or a faster surface-speed than the crimping-rolls, and the laying-wheels at a faster surface-speed than either pressure or crimping rolls, substantially as described.

9. In a machine for forming and pressing plaits in a strip of fabric, the combination, with two grooved crimping-rolls, two feed and pressing rolls, means for imparting the same or a higher surface-speed to the latter than that of the crimping-rolls, and a guide-plate constituting, conjointly with one of said feed-rolls, a channel for the goods, of a laying mechanism and of means for imparting a higher surface-speed to the latter than that of either the crimping or feed rolls, substantially as described.

10. In a machine for forming and pressing plaits in a strip of fabric, the combination, with two grooved crimping-rolls, two feed and pressing rolls, means for imparting a higher surface-speed to the latter than that of the crimping-rolls, and a slotted guide-plate constituting, conjointly with one of said feed-rolls, a channel for the goods, of a laying mechanism operating through the slots in said guide-plate and of means for imparting a higher surface-speed to said laying mechanism than that of either the crimping or feed rolls, substantially as described.

11. In a machine for forming and pressing plaits in a strip of fabric, the combination of a laying mechanism, a slotted guide-plate, and a feed-surface, with one or more rollers arranged to press gum cords upon the plaited goods through said slotted guide-plate, substantially as described.

12. In a machine for forming and pressing

plaits in a strip of fabric, two crimping-rolls grooved with ratchet-teeth and arranged to intermesh, so that the goods are delivered from them with crimps having one inclined and one vertical portion, in combination with laying mechanism, feeding mechanism, devices for imparting a more rapid surface speed to the laying mechanism than that of either the crimping-rolls or the feed mechanism, and a channel for the goods, extending between the laying mechanism and the feed mechanism, substantially as described.

13. In a machine for forming and pressing plaits in a strip of fabric, the combination, with two crimping-rolls having oblique and vertical ratchet-teeth, of laying and pressing mechanism, the teeth in said crimping-rolls being so set as to deliver the goods with the vertical side of each crimp toward the laying and pressing mechanism, substantially as described.

14. In a machine for forming plaits in a strip of fabric, a table over which the goods pass as they enter the machine, two longitudinally-grooved crimping-rolls provided with oblique and vertical ratchet-teeth, and arranged to deliver the goods with the vertical side of the crimps forward, a series of laying-wheels operating through slots in the guide-plate and laying the crimps all one way as the goods pass between the under surface of the guide-plate and the upper surface of one of a pair of feed and pressure rolls, all combined and arranged to operate substantially as herein specified. 25 30
